Della L. Seif,

ATTORNEY

UNITED STATES PATENT OFFICE.

DELLA L. SEIF, OF GALION, OHIO.

COLLAR-BUTTON.

1,293,948.

Specification of Letters Patent. Patented Feb. 11, 1919.

Application filed June 22, 1917. Serial No. 176,400.

To all whom it may concern:

Be it known that I, DELLA L. SEIF, a citizen of the United States, residing at Galion, in the county of Crawford and State of Ohio, have invented certain new and useful Improvements in Collar-Buttons, of which the following is a specification.

This invention relates to a collar or like button and the principal object of the invention is to provide means for preventing the button from being misplaced or dropped and lost.

Another object of the invention is to provide means whereby the button may be detached from the before mentioned means whenever desired.

Another object of the invention is to provide means for securing the button to the shirt by a chain or the like, so if the button should be dropped it will be retained by the chain and thus not be lost by dropping on the floor and rolling under the furniture.

Another object of the invention is to provide means for attaching the chain to a tie clasp so as to make this clasp serve two purposes, thus reducing the expense of the article.

Another object is to facilitate the placing of the button in the button hole by means of the chain.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings, wherein like characters denote like or corresponding parts throughout the several views, and in which:

The figure shows the collar button with my improvement attached thereto.

In this drawing, the collar button is indicated at 1 and the tie clasp at 2. 3 indicates the chain secured to the tie clasp in any desirable manner and to the button by means of a ring 4. I prefer to make this ring of the well known spring type, so that the same may be opened to release the button or to place the button therein and which will spring back into its original shape.

The drawing shows the button provided with a recess 5 in the lower part of its shank 55 into which the spring ring is placed, but my invention may be applied to other styles of buttons, for instance, the ring may inclose the entire shank.

I do not wish to be limited to the tie clasp, 60 as the chain may be secured to the shirt by any suitable means, such as a safety pin. However, by using the tie clasp, the clasp is made to serve a double purpose and the expense of the article is thereby reduced and 65 a much neater arrangement is secured.

It will be seen that if the button should be dropped it will not be lost, as the chain prevents it from dropping on the floor. Furthermore, the chain may be made to 70 facilitate the placing of the button in the hole, as by passing the chain through the hole first would aid in drawing through the head of the button. Furthermore, if desired the ring may be caused to pass through 75 the button hole, so as to hold the shirt between the bottom of the button and the said ring, thereby preventing the button from projecting inwardly beyond the shirt and coming in contact with the neck of the 80 wearer.

It is thought from the foregoing that the advantages and novel features of my invention will be readily apparent.

I desire it to be understood that I may 85 make slight changes in the construction and in the combination and arrangement of the several parts, provided that such changes fall within the scope of the appended claim.

I claim as my invention:

In combination with a collar having a pair of button holes, a collar button having an opening in its shank adjacent the base of the button, a ring engaging the said opening adapted to pass through one of the button holes, and thus hold the base of the collar button in close engagement with one side of the collar, a clasp, and a chain connecting the ring with said clasp. 95

In testimony whereof I affix my signature 100 in presence of two witnesses.

DELLA L. SEIF.
